COLUMN FOR A TROPHY BASE

Marvin Kramer and Harry A. Dorn, Chicago, Ill., assignors to General Classics, Incorporated, Chicago, Ill., a corporation of Illinois

Application March 21, 1958, Serial No. 50,126

Term of patent 3½ years

(Cl. D29—23)

FIG. 1

FIG. 2

FIG. 3

FIG. 4

Fig. 1 is a front elevational view of a column for a trophy base embodying our new design;

Fig. 2 is a side elevational view of the same;

Fig. 3 is a rear elevational view of the same; and

Fig. 4 is a sectional view taken on the plane of line 4—4 in Fig. 1 of the drawings and viewed upwardly in the direction indicated.

The side of the ornamental column not shown is substantially the same as the side shown.

The broken lines showing of a top and bottom pedestal is for illustrative purposes only.

We claim:

The ornamental design for a column for a trophy base, substantially as shown and described.
